US00D583135S

(12) **United States Design Patent**
Mariman et al.

(10) **Patent No.:** **US D583,135 S**
(45) **Date of Patent:** **** Dec. 23, 2008**

(54) **PORTION OF A FOOTWEAR SOLE**

4,327,503 A * 5/1982 Johnson ..... 36/32 R
D294,655 S 3/1988 Heyes

(75) Inventors: **Martin Mariman**, Hampton, NH (US);
Alexander Dardinski, Newburyport, MA (US); **Peter Dillon**, Topsfield, MA (US)

(Continued)

(73) Assignee: **New England Footwear, LLC**,
Portsmouth, NH (US)

DE 33 17 462 10/1983

(**) Term: **14 Years**

(Continued)

(21) Appl. No.: **29/263,684**

(22) Filed: **Jul. 27, 2006**

Primary Examiner—Ian Simmons
Assistant Examiner—Anna J Burmeister
